US0D1035226S

(12) **United States Design Patent** (10) Patent No.: **US D1,035,226 S**
(45) Date of Patent: ** Jul. 16, 2024

(54) **FOOTWEAR**

(71) Applicant: **Crocs, Inc.**, Broomfield, CO (US)

(72) Inventors: **Alexander Jacob Mayhew**, Denver, CO (US); **Catherine Lam**, New York, NY (US)

(73) Assignee: **Crocs, Inc.**, Broomfield, CO (US)

(**) Term: **15 Years**

(21) Appl. No.: **29/850,020**

(22) Filed: **Aug. 16, 2022**

(51) LOC (14) Cl. **02-04**

(52) U.S. Cl.

USPC **D2/947**

(58) **Field of Classification Search**

USPC D2/896, 900, 902, 904, 906–908, D2/916–924, 925–945, 947–960, 969–979
